UNITED STATES PATENT OFFICE.

JAMES W. PAUL, OF DAVIS, WEST VIRGINIA.

PORTABLE SIGNAL APPARATUS FOR MINES.

1,102,793.

Specification of Letters Patent.

Patented July 7, 1914.

Application filed May 5, 1914. Serial No. 836,586.

(DEDICATED TO THE PUBLIC.)

To all whom it may concern:

Be it known that I, JAMES W. PAUL, a citizen of the United States, residing at Davis, Tucker county, West Virginia, have 5 invented an Improved Portable Signal Apparatus for Mines, of which the following is a specification.

This application is made under the act of March 3, 1883, chapter 143, U. S. Statute 10 XXIII, page 625, and the invention herein described and claimed may be used by the Government of the United States or by any of its officers or employees in the prosecution 15 of work for the United States, or by any person in the United States, without the payment of any royalty thereon.

My invention relates to portable signaling apparatus particularly adapted for use in mine-rescue work. In work of this character 20 it is a desirable object to provide an efficient signaling means between the rescuing operator who descends the mine shaft and the operators in charge at the head of the shaft and in the engine house, and, further, 25 to so construct the signaling means that should the rescuing operator be disabled or overcome by gas or should the signaling apparatus be rendered inoperative, an alarm will be automatically sounded at the head of 30 the shaft and in the engine room.

My invention is designed to accomplish the above object. Its nature and characteristic features will be readily understood 35 from the following description taken in connection with the accompanying drawings, wherein—

Figure 1 is a perspective view of the apparatus as a whole. Fig. 2 is a front elevation, partly broken away and in section, of 40 a casing or trunk which carries a winding reel and other parts of the signaling apparatus. Fig. 3 is a diagrammatic view showing the circuit connections.

Referring to the above views, and particularly to Figs. 1 and 2, the parts of the apparatus placed adjacent the head of the shaft are inclosed in a casing or trunk having an upper and a lower compartment. Access to these compartments may be had through hinged side 45 doors 1 and 2 and a removable cover 3. A winding reel carrying a cable 7 of any suitable length, say 2,500 feet, is journaled in the upper compartment. The reel is composed of a hollow barrel 5, preferably of

brass, and end flanges 8 of steel. Steel plugs 9 having their outer ends reduced to form stub shafts 10 are fastened in the two ends of the barrel and the stub shafts are journaled in bearings formed in the trunk. One 60 of the stub shafts extends through the side of the trunk; its outer extension being further reduced to receive the sleeve 11 of crank 12. The crank is preferably made removable. On the outer face of one of the 65 reel flanges, two concentric collector rings 13 and 14 are attached, suitable insulating material being placed between the rings and flange. Brushes 15 and 16 mounted in the trunk contact with the rings 13 and 14, respectively. The cable 7 includes two insulated wires 17 and 18, the inner ends of which are threaded through an oblique hole 19 drilled through the barrel 5, plug 9, and flange 8 and are then connected to the collector rings 14 and 13, respectively. 70

The lower compartment of the trunk carries two batteries 20 and 21, a relay 22 and a bell 23. The relay and bell are secured to the inner face of the door 1.

Switch sockets 24 and 25, adapted to receive two-pole plug switches 26 and 27, are formed in the side of the trunk. When the apparatus is not in use the plug switches are removed.

The outer or free ends of conductors 17 and 18 are adapted to be connected to binding posts on a plate 24 secured to the top of a box 25.

26' and 27' are straps attached to the box 90 affording a convenient means for attaching the box to the body of an operator. For a right handed operator, the box is carried at the right side, the strap 26' being placed over the left shoulder and the strap 27' 95 around the waist.

28' is a bell secured to the side of the box and 29 is a protecting shield for the bell. The battery 30' (Fig. 3) is carried in the box.

A switch lever 30 is pivoted on the board 24' 100 and is urged or biased by a compression spring 31 to make contact with the terminal 32, but, when the apparatus is being used, it is held down by the operator in contact with terminal 33.

To assemble the apparatus for use, the trunk is placed adjacent the head of the mine shaft, the doors 1 and 2 are unhooked and opened, and the cover 3 removed, exposing the reel, signal bell and relay. An 110

operator is stationed at the trunk to pay out the cable or wind it in as required. The rescuer straps the box 25 to his side and grasping the switch lever 30 and holding it firmly down on its lower contact 33, he steps into the cage and is lowered in the shaft, the cable 7 being paid out according to the rate of his descent.

When the switch lever 30 is held down in contact with the lower terminal 33, the condition of the circuits is as shown in Fig. 3. The primary circuit, composed of the battery 21, brush 15, collector ring 13, conductor 18, contact 33, switch lever 30, conductor 17, collector ring 14, brush 16, two-pole plug switch 24, 26, and relay 22, is closed. The relay 22 is holding open the bell circuit, comprising the battery 20, socket 25, engine house bell 34, socket 25, trunk bell 23, and house bell 34, socket 25, trunk bell 23, and 20 the armature and back contact of relay 22. The circuit of bell 28 and battery 30' is held open at the upper contact 32. When the engine house bell 34 is not needed, it may be disconnected from the socket terminals 25 and these terminals connected by the plug switch 27. The rescuer can now signal to the operators at the head of the shaft by manipulating the switch lever 30, intelligence being communicated through any pre-25 arranged code of signals. The bell 28 is provided to facilitate the transmission of signals by acting as a sounder to repeat the movements of the switch 30. It would also enable the rescuer to be readily located 30 should the cable be broken and he be overcome or disabled while out of the cage or bucket.

It will be seen from the above that I have provided a signaling system, in which the primary circuit or the circuit which connects the rescuer with the apparatus at the head of the shaft, is normally closed by a switch positively held by the rescuer. If the latter should be overcome through any of the various causes incident to the hazardous nature of his work, or if the cable should break or any of the connections in the primary circuit should be disrupted, the relay 22 would instantly release its armature and cause a continuous ringing of the bells at the trunk and in the engine house. This would, in every case, be the signal to hoist immediately.

While my invention is designed and is particularly adapted for use in the rescue work of mines it is obviously capable of application in various other situations where it is desirable to establish communication between a moving operator and a relatively stationary operator.

Having fully described the structure and mode of operation of my improved apparatus, I claim as my invention:

1. A circuit including a portable switch, 65 a source of current and a translating device,

means for coiling and uncoiling a portion of the circuit between the switch and translating device, said switch being biased to move to one position and a signal controlled by said translating device and rendered active when the switch is in its biased position. 70

2. A signaling apparatus comprising a metallic circuit including a portable switch and a translating device, means for coiling and uncoiling the conductors forming a portion of the two sides of the circuit between the switch and translating device, said switch being biased to move to one position and being adapted to be carried by an operator and to be normally held by him away 75 from its biased position, and a signal controlled by said translating device and rendered active upon movement of the switch to its biased position. 80

3. A signaling apparatus comprising a metallic circuit including a portable switch, a battery and a magnet, means for winding the conductors forming a portion of the two sides of the circuit in a coil, said winding means being between the switch and magnet, 90 whereby the distance between the same may be varied at will, said switch being adapted to be carried by an operator and to be held by him in position to close said circuit, means for automatically moving the switch when released, to open the circuit, and a signal rendered active upon deenergization 95 of said magnet. 100

4. A signaling apparatus comprising a reel, a pair of insulated conductors arranged side by side and wound on the reel, a portable switch adapted to be manually held in position to connect the free ends of the conductors, but biased to move away from such position when released, normally closed electrical connections between the other ends of said conductors, said connections including a magnet, and a signal actuated upon deenergization of said magnet. 105

5. A signaling apparatus comprising a reel, a pair of insulated conductors wound on the reel and forming a portion of the two sides of an electrical circuit, a portable switch connected with the outer ends of said conductors, and adapted to be normally held 110 in position to connect said ends, but biased to move away from such position when released, normally closed connections between the inner ends of said conductors, said connections including a translating device, a source of energy for the normally closed circuit formed by said conductors, switch, and electrical connections, and a signal rendered active upon the opening of said circuit. 115

6. The combination of a reel a cable wound on the reel and including a pair of insulated conductors, a support and means for attaching the same to the body of an operator, the outer ends of the conductors be- 120 130

ing connected to the support, a switch on the support biased to one position, a circuit including said conductors and closed when the operator is holding the switch away 5 from its biased position, a signal actuated upon the opening of said circuit, and a second signal actuated upon the movement of said switch to biased position.

7. A portable signaling apparatus comprising a casing, a reel journaled in the casing, a pair of substantially coextensive insulated conductors, partly wound on the reel, a pair of collector rings attached to the reel and connected with the inner ends of the 15 conductors, a pair of brushes contacting

with the collector rings, electrical connections between the brushes, said connections including a battery and a relay, a support having means of attachment to the body of an operator and connected to the outer ends 20 of the conductors, a switch and a signal mounted on the support, a circuit including the signal, said switch being operable to alternately connect the outer ends of the conductors and close said circuit, and a signal 25 controlled by said relay.
